(57) **CLAIM**

The ornamental design for a hair clipper housing with gripping formations, as shown and described.

DESCRIPTION

FIG. 1 is a top perspective view of the hair clipper housing with gripping formations;

FIG. 2 is a top view of same;

FIG. 3 is a side view of the hair clipper housing with gripping formations, both sides being mirror images of each other;

FIG. 4 is a bottom view of same;

FIG. 5 is a front view of the housing of FIG. 1; and

FIG. 6 is a rear view of same;

FIG. 7 is a top perspective view of a second embodiment of the hair clipper housing with gripping formations;

FIG. 8 is a top view of same;

FIG. 9 is a side view of the hair clipper housing with gripping formations of FIG. 7, both sides being mirror images of each other;

FIG. 10 is a bottom view of same;

FIG. 11 is a front view of the housing of FIG. 7; and

FIG. 12 is a rear view of same;

FIG. 13 is a top perspective view of a third embodiment of the hair clipper housing with gripping formations;

FIG. 14 is a top view of same;

FIG. 15 is a side view of the hair clipper housing with gripping formations of FIG. 13, both sides being mirror images of each other;

FIG. 16 is a bottom view of same;

FIG. 17 is a front view of the housing of FIG. 13; and,

FIG. 18 is a rear view of same.

The broken lines illustrate portions of the hair clipper housing with gripping formations and form no part of the claimed design.
